UNITED STATES PATENT OFFICE.

RUDOLPH I. SCHONITZER, OF SPRINGFIELD, OHIO, ASSIGNOR TO SCIENTIFIC STEEL WOOL COMPANY, OF OWENSBORO, KENTUCKY, A CORPORATION OF DELAWARE.

METHOD OF MAKING METAL WOOL AND SHAVINGS.

1,419,473.

Specification of Letters Patent. Patented June 13, 1922.

Original application filed April 16, 1919, Serial No. 290,499. Divided and this application filed August 22, 1919. Serial No. 319,225.

To all whom it may concern:

Be it known that I, RUDOLPH I. SCHONITZER, a citizen of the United States, residing at Springfield, in the county of Clark and 5 State of Ohio, have invented new and useful Improvements in Methods of Making Metal Wool and Shavings, of which the following is a specification.

This invention relates to the production 10 of the so called metal wool or steel wool and shavings and is a division of my co-pending application filed April 16, 1919, Serial Number 290,499.

The object of the invention is to provide 15 certain new and useful improvements as will be hereinafter more fully described, shown in the accompanying drawings, and particularly pointed out in the appended claims, it of course being understood that changes 20 in the form, proportion, size and minor details may be made, within the scope of the claims, without departing from the spirit or sacrificing any of the advantages of the invention.

25 Figure 1 is a central vertical sectional view of a metal wool machine embodying the features of the present invention, the work carrying chuck being shown in elevation;

Figure 2 is a vertical central sectional 30 view of the work driver and work holding chuck on an enlarged scale;

Figure 3 is a top plan view of Figure 2, the adjusting hand wheel being broken away;

35 Figure 4 is a sectional elevation of one of the cutter holders and feeders on an enlarged scale;

Figure 5 is the side elevation of the lower half of Figure 4, looking at the right hand side thereof;

40 Figure 6 is a fragmentary elevation of the bottom portion of Figure 4, looking at the left hand side thereof, parts being broken away to show the adjustable mounting of the gage foot;

Figure 7 is a detail view on line 7-7 of Figure 5;

Figure 8 is a detail section on the line 8-8 of Figure 5;

50 Figure 9 is a detail sectional view on the line 9-9 of Figure 4;

Figure 10 is a fragmentary elevation, on an enlarged scale, illustrating the operation of successive cutters.

One embodiment of means for carrying 55 out the present invention has been shown in the accompanying drawings and includes a work-holder and driver A rotating in a substantially horizontal plane, mounted upon a support B, preferably in the form of an upright standard, and a tool holder and cutter C mounted above the work-holder and designed to carry a cutting tool held in cooperative relation with a work-piece D in the form of a cylinder. As illustrated, the 60 tool holder supports the tool in cooperative relation with the upper edge of the cylindrical work-piece, the tool being stationary and the work-piece being rotated, whereby strands or shavings are cut from the upper 65 edge of the work-piece. It will here be explained that the cutting operation is continuous, in the sense that the work-piece is rotated continuously in the same direction and the cutting tool is automatically fed 70 towards the work-piece so as to always remain in cutting relation thereto as the length or height of the work-piece diminishes under the cutting or shaving action of the cutter. It will of course be understood that a plurality of cutter holders and feeders are employed, and arranged in a circular series. 75 Each holder and feeder is entirely independent of each of the other holders and feeders, as will be hereinafter more fully described. 80

For the support of the apparatus, I preferably construct a masonry foundation 1, the top of which is at the floor level 2. Within the foundation is a pit 3, and within the bottom of the pit is embedded a base 90 member 4, preferably of wood. The diameter of the base member 4 is less than the diameter of the pit so as to leave an annular space 5 for a purpose as will be hereinafter described. 85

Rising centrally from the top of the base 4 is the standard B, the bottom of which is rigidly secured within a base flange 6 suitably secured to the top of the base 4, as by fastenings 7. It will be noted that the 95 support or standard B rises a suitable distance above the open top of the pit. Surrounding and overhanging the open top of the pit is a base plate 8 provided with a concentric opening 9 of a diameter large enough 100 to permit of the downward introduction therethrough of the base flange 6. Upon the top of the base plate 8 is a supporting

ring 10 secured thereto by suitable fastenings 11. Within the ring 10 is a rotating hanger 12 of substantially cylindrical shape, provided at its upper edge with an external 5 depending cylindrical flange 13 constituting the upper member of a bearing, the lower member 14 of which is provided upon the ring 10. Suitable antifriction devices 15 are provided between the bearing members 13 10 and 14, thereby constituting a thrust-bearing. If desired, a dust-excluding packing 16 may be provided between the bearing members 13 and 14. Hung from the hanger 12 is a cylindrical hub 17 concentric with 15 the standard B and provided at its lower end with a driving wheel 18 to which power may be applied in any suitable manner. As shown in the drawings, the driving wheel 18 is of conical form and power is applied 20 thereto by another conical wheel 19 mounted upon a shaft 20, extending transversely outward through a tunnel or opening 21 formed through the foundation 1. This tunnel also serves as a means of access to 25 the pit 3 for purposes of mounting the apparatus and for purposes of general inspection and repairs. While toothed gearing may be employed, a friction drive is preferred, as shown in the drawings. Top and 30 bottom anti-friction annular bearings 22 and 23 are employed between the hub 17 and the standard B, a suitable spacing sleeve 24 being employed to maintain the bearing 22 and 23 spaced at the desired distance. The 35 hub 17 and the driving wheel 18 are of relatively massive construction in order to operate as a counter-balance for the heavy construction which rotates about the upper portion of the post or standard B.

40 Disposed above the hanger 12 is a ring 25 supported by a plurality of upstanding arms 26 rising from the hanger 12. At suitable intervals around the ring 25 there are set screws 27 which pierce upstanding projections 28 on the ring, and are designed to engage the exterior of the work-piece D. The set screws 27 are not intended as the sole support of the weight of the work-piece D, as the latter is otherwise supported, as 45 will be hereinafter explained. The main purpose of the set screws 27 is to afford a driving connection between the work-piece D and the driving ring or member 25, whereby the work-piece is rotated concentrically about the post or standard B.

At a suitable distance above the sleeve 24 there is an externally screw-threaded sleeve 29, and between the bearing 22 and the threaded sleeve 29 is a spacing sleeve 30. 50 The sleeve 29 is fixed against rotation upon the post or standard B by means of suitable pins or keys 31 extending through notches in the bottom of the sleeve 29 and entering openings in the post or standard B. A nut 60 32 is mounted upon the threaded portion of

the sleeve 29, and is provided on its upper face with an annular raceway containing anti-friction devices 33. A suitable bearing member 34, in the form of a ring, is supported upon the anti-friction devices 33 70 and is capable of rotating upon the nut 32. Upwardly extending and outwardly diverging arms 35 rise from the nut 32 and carry at their upper ends a hand wheel 36, for use in turning the nut 32, so as to work the 75 latter up and down upon the post or standard B. Arms 37 extend upwardly and outwardly from the rotatable bearing member 34 and carry at their upper ends a ring 38. Supported upon the ring 38 is a series of 80 segments 39, each of which is provided upon its outer convex end with an upright flange 40 extending above and below the segment. Each segment is provided with inner and outer slots 41 and 42 receiving headed studs 85 43 and 44 rising from the ring 38. The studs 43 and 44 guide the segment 39 during the adjustment thereof which is radial to the post or standard B, and the ends of the slots 41 and 42 limit the movement of 90 the segment in opposite directions. A pair of helical springs 45 have their outer ends connected to a stud or post 46, rising from an intermediate portion of the segment 39, and their rear ends connected to the respective studs 43. Said springs are normally 95 under tension with a tendency to move the segment inwardly towards the post or standard B, so that when outward pressure is removed from the segment it will be automatically drawn inwardly so as to relieve the pressure of its flange portion 40 from the inner wall of the work-piece D.

100 It will here be explained that the series of segments 39 constitute a centering device for 105 centering the work-piece D within the driving element 25 and also to bring the work-piece to true cylindrical form. For the purpose of forcibly moving the series of segments 39 radially outward, there is provided 110 a nut 47 mounted upon the threaded upper portion 47' of the post or standard B. This threaded portion of the post is of reduced diameter and extends a suitable distance into the open upper end of the screw-threaded sleeve 29, whereby an annular space 48 is provided and into which the lower end portion of the nut 47 may descend when the latter is adjusted downwardly. On the top of the nut 47 is secured a hand wheel 49 for 115 convenience in adjusting the nut. A wedge shaped or downwardly tapered sleeve 50 embraces and is carried by the upper portion of the nut 47, the outer or tapering face of the sleeve fitting within the hub portions 51 120 at the inner ends of the segments 39, the faces of which are inclined in accordance with the inclination of the exterior of the cone or wedge 50. The cone 50 is hung upon the upper end portion of the nut 47 in any 125 130

suitable manner, for instance, as shown in the drawings. It will now be understood that the nut 47 may rotate within the cone or wedge 50, whereby the latter will be 5 moved upwardly and downwardly without rotation. Downward movement of the wedge 50 will force the segments 39 radially outward into engagement with the inner periphery of the tubular work-piece D, while 10 upward movement of the cone or wedge 50 will result in releasing the segments 39 so as to permit of the latter being drawn inwardly and out of engagement with the work-piece D by reason of the action of the 15 springs 45.

As thus far described, it will be seen that the nut 32 which carries the internal chuck made up of the segments 39, is capable of being adjusted vertically by manipulation of 20 the hand wheel 36, whereby the internal chuck may be lowered until the upper hand wheel 49 is below the top of the driving ring 25, whereupon the work-piece D may be placed sidewise within the ring 25 without 25 interference by the internal chuck. Preparatory to placing the work-piece D within the driving element 25, pieces of wire, chips or the like, are placed upon the top of the member 25 so as to temporarily support the 30 work-piece out of engagement with the top of the ring 25. After the work-piece has been thus put in place, the hand wheel 36 is manipulated to move the internal chuck upwardly and into the tubular work-piece D, 35 whereupon the hand wheel 49 is manipulated to move the wedge 50 downwardly and expand the chuck until the work-piece D is snugly gripped and supported by the chuck and also brought into true circular form. 40 When this is done the set screws 27 are set up tightly against the work-piece D and the pieces of wire, chips or the like are removed from beneath the work-piece D. By temporarily supporting the work-piece D above 45 and out of contact with the driving ring 25, said work-piece D is relatively loose and in condition to conform itself to the circular shape of the internal chuck without interference on the part of the driving ring 25. 50 The work-piece having thus been gripped by the chuck and connection made between the driving member 25 and the work-piece D by means of the set screws 27, the work-piece may be rotated by applying power to the 55 driving wheel 18, as motion is translated therefrom through the hub 17, the hanger 12 and the arms 26.

As hereinbefore set forth, a series of cutter holders and feeders C are disposed above 60 and in cooperative relation with the upper edge of the work-piece D. As these cutter holders and feeders are duplicates in construction, mounting and manner of operation, a detailed description of one of them is 65 deemed sufficient. Each cutter holder and

feeder is disposed above the work piece D, is capable of gravitating into cooperative relation therewith and is hung from the bottom of a suitable tank or reservoir 53, supported upon standards 54 rising from the 70 base plate 8 to which said standards are bolted or otherwise secured. This tank or reservoir is designed to contain fluid under pressure which may be admitted to each cutter holder and feeder for the purpose and in 75 the manner as will be hereinafter described.

Each cutter holder and feeder includes a cylinder 55 surmounted by a valve casing 56 which is hung from the bottom of the tank 53 by means of a short pipe section 57. The 80 valve stem 58 of the valve 56 is accessible at the exterior of the casing 56 for convenience in opening and closing the valve thereof. Working within the cylinder 55 is a rod 59 provided upon its upper end with a suitable 85 piston 60 working in the cylinder 55 and subject to pressure admitted into the upper end of the cylinder through the valve casing 56 and from the tank or reservoir 53. The rod 59 projects a suitable distance below the 90 cylinder 55 and is guided in a tubular guide member 61 hung from the lower end of the cylinder 55. An inverted substantially U-shaped yoke 62 is hung from the lower end of the rod 59, which projects through the 95 open bottom of the guide 61. The inner sides of the upright arms of the yoke 62 are provided with guideways 63 in which works a cross head 64 having depending arms 65 which also work in the guide 63 and project 100 through the open bottoms thereof. Between the cross-head 64 and the bottom of the rod 59 is an adjusting member 66 provided with a screw-threaded stem 67 extending into a screw-threaded socket in the bottom of the 105 rod 59. A stud 68 depends centrally from the member 66 and is provided with a circular head 69 rotatably received within a flanged notch or seat 70 in the top of the cross head 64. By rotating the member 66, which 110 is accessible at the opposite open sides of the yoke 62, the cross-head 64 may be raised and lowered. Upstanding finger pins 71 may be provided upon the member 66 for convenience in manipulating the same. Carried by 115 and extending between the arms 65 is a cross-bar 72 that is embraced by a clamp 73 having a cutter holder 74 at its lower end. The clamp 73 may be adjusted lengthwise of the cross-bar 72, and also rotatably adjusted 120 thereon so as to bring the cutter holder into any desired position. The cutter 75 is held in a seat or guideway in the lower portion of the holder 74 and is adjustable endwise therethrough. A suitable clamping screw 76 is 125 employed for holding the cutter when set to any adjusted position. The cutter 75 is a flat bar having a chisel edge 77 at its forward and lower end which is in cooperative relation with the upper edge of the work-piece D, 130

which latter rotates beneath the cutter and the latter cuts a chip or strand therefrom.

For convenience in mounting the cutter holder 74 upon the cross-bar 72, the arm 65 is bifurcated in order that the bar 72 may be placed endwise through the bifurcation and into engagement with the opposite arm 65, the latter being provided with a non-circular seat or socket 78 to receive the similarly shaped end portion 79 of the bar 72, whereby the latter is held against rotation. A clamping screw 80 is employed to draw together the sides of the bifurcated arm 65 so as to clamp the same upon the bar 72 and hold it firmly in place.

Disposed in front of the cutter 75 there is a gage member which preferably includes a roller 81 to travel upon the top edge of the work-piece D, and carried in a forked arm 82 depending from the lower end of a substantially L-shaped bracket 83, secured to the rod 59 at a point between the bottom of the guide 61 and the yoke 62. The foot or roller 81 is adjustable transversely of the cutter by means of a hand wheel 84 on a screw-threaded stem 85 having a swiveled connection 86 with the upper portion of the arm 82, which is mounted to slide in a guideway in the lower end of the bracket 83. It will here be explained that the bracket 83 and foot 81 are fixed upon the rod 59 against movement longitudinally on said rod, while the cutter holder 74 is adjustable vertically for the purpose of obtaining any desired depth of cut, in order to produce the different desired gages of steel wool. In order that any predetermined depth of cut may be obtained in accordance with the desired gage of steel wool to be produced, the body of the adjusting member 66 is circular in form and provided on its peripheral edge with a scale, as best shown in Figure 5 of the drawings, and in cooperative relation with the scale is a pointer or index 87 carried by a bracket 88 secured to the cross head 64.

In the operation of the machine or apparatus, the hand wheel 36 is manipulated to feed the nut or member 32 downwardly until the hand wheel 49 is below the top of the driving member 25, whereupon the tubular work piece D may be introduced sidewise between the driving member 25 and the series of shaving cutters, and into operative position. The hand wheel 26 is then manipulated to feed the nut 32 upwardly and thereby bring the internal chuck upwardly and into the tubular work piece at any desired position therein. The hand wheel 49 is then manipulated to screw downwardly the nut 47 and thereby force outwardly the chuck members 39 into engagement with the interior walls of the work piece, whereby the latter will be brought to true circular form and also held rigidly upon the chuck. The

set screws 27 are then set up tightly against the work piece. Prior to fitting the work piece in place, the cutter holders are forced upwardly out of the way. In order that the cutter holders may be forced upwardly, a relief valve 89 is provided in the upper portion of each cylinder 55 so that by opening the valve, a communication is established between the interior of the upper portion of the cylinder 55 and the atmosphere so as to permit of the escape of air from the cylinder 55 when the cutter is pushed upwardly. After having thus been pushed upwardly to its upper limit, the cutter will remain in its elevated position until again brought down by hand into engagement with the upper edge of the work piece. Before bringing the shaving cutter into engagement with the work-piece, it is adjusted vertically by manipulation of the member 66 until the cutter has been brought to the proper position, with respect to the gage 81, to give the desired depth of cut. After this adjustment has been made and the cutter brought down into operative relation to the work piece, fluid pressure is admitted into the upper end 90 of the cylinder so as to place the desired pressure upon the shaving cutter 75, whereby the cutter is forced down into the work piece as far as will be permitted by the gage 81 when it comes into contact with the upper 95 edge of the work piece. The gage 81 travels upon the top edge of the work piece and thereby limits and accurately gages the depth of the cut of the shaving cutter 75 in a very simple and efficient manner. When 100 the several cutters have been adjusted and brought into operative position with respect to the work piece D, power is applied to the driving wheel 18, whereby the work piece D will be rotated and shavings will be cut 105 from the top edge of the rotating work in the manner as clearly shown in Figure 10 of the drawings. It will here be explained that the successive shaving cutters are set or adjusted in progressive relation, which relation is maintained by reason of the pressure upon the cutters and the fact that the gage members 81 are in engagement with the top edge of the work piece. The rotation of the work piece is continued until the work 115 piece has been reduced to the point where the cutters are adjacent the top of the flange 40 of the internal chuck, whereupon the driving operation is stopped, the internal chuck is released from the work piece by 120 manipulation of the hand wheel 49, and then the hand wheel 36 is manipulated to feed the internal chuck downwardly to a lower position within the tubular work piece, and then the hand wheel 49 is manipulated in the opposite direction to set the chuck members 39 tightly against the work piece. After this adjustment of the

internal chuck, operation of the machine is resumed until the work piece has been reduced as far as it is desired to go.

It will here be explained that I employ a truly circular single thickness tubular work piece as distinguished from a tubular work piece wound in spiral laminations. One of the important advantages of a truly cylindrical tubular work piece is that the cutting edge of the shaving cutter is maintained in the most effective cutting relation to the work without requiring any automatic adjusting or shifting of the cutter during the operation of the machine.

It will further be explained that each cutter rod 59 is slideable in and guided by the guide member 61, and is capable of gravitating so as to bring the cutter 75 into cutting relation with the top edge of the work-piece.

D. For some grades of metal wool and shavings, the weight of the cutter bar 59 and associated parts is alone sufficient to maintain the cutter in cutting relation with the work-piece. For other grades of wool and shavings and under certain conditions, additional pressure may be applied to the cutter through the cutter bar 59, as for instance by applying fluid pressure to the upper end of the cutter bar 59 in the manner hereinbefore described.

While the fluid pressure is employed to maintain a downward pressure upon the shaving cutter, said fluid pressure will also permit yielding of the cutter to any uneven places in the upper edge of the work-piece, and it will also permit the cutters to yield and accommodate themselves to any wobbling motion of the work-piece which must of necessity occur, as it is impossible to produce and maintain an accurate rotation of the work-piece. Moreover the use of fluid pressure for maintaining the work and cutters in cooperative relation is of course not limited to any particular shape of work-piece.

What I claim is:

1. The method of making metal wool and shavings, consisting in interiorly supporting a metal tube of a single thickness, subjecting one end of the metal tube to the action of a shaving cutter, and maintaining the tube and cutter in cutting or shaving relation as the length of the tube diminishes under the action of the cutter.

2. The method of making metal wool and shavings, consisting in interiorly supporting a metal tube of a single thickness, rotating the tube about the longitudinal axis thereof, subjecting one end of the tube to the action of a shaving cutter, and maintaining the tube and cutter in cutting or shaving relation as the length of the tube diminishes under the action of the cutter.

3. The method of making metal wool and shavings, consisting in interiorly supporting

a metal tube of a single thickness, subjecting one end of the metal tube to the action of a shaving cutter, maintaining the tube and cutter in cutting or shaving relation as the length of the tube diminishes under the action of the cutter, and shifting the tube upon its interior support and in the direction of the axis of the tube to bring uncut portions of the tube into position to be cut.

4. The method of making metal wool and shavings, consisting in interiorly supporting a metal tube of a single thickness, rotating the tube about the longitudinal axis thereof, subjecting one end of the tube to the action of a shaving cutter, maintaining the tube and cutter in cutting or shaving relation as the length of the tube diminishes under the action of the cutter, and shifting the tube upon its interior support and in the direction of the axis of the tube to bring uncut portions of the tube into position to be cut.

5. The method of making metal wool and shavings, consisting in taking a metal tube and bringing it to true cylindrical form, bringing a shaving cutter into cutting relation with one end of the tube and effecting a relative rotation of the members on the longitudinal axis of the tube as a center.

6. The method of making metal wool and shavings, consisting in taking a metal tube and bringing it to true cylindrical form, rotating the tube in its cylindrical form upon an upright axis, and bringing a shaving cutter into cutting relation with the top edge of the tube.

7. The method of making metal wool and shavings, consisting in mutually setting a series of shaving cutters and gages for progressively deeper cuts, bringing the cutters into cutting relation with a metal work-piece and the gages in cooperative relation thereto, effecting relative movement between the cutters and the work-piece to progressively cut shavings therefrom, and maintaining the work-piece and cutters in an elastically yieldable cutting relation.

8. The method of making metal wool and shavings, consisting in mutually setting a series of shaving cutters and gages for progressively deeper cuts, bringing the cutters into cutting relation with a metal work-piece and the gages in cooperative relation thereto, effecting relative movement between the cutters and the work-piece to progressively cut shavings therefrom and imparting an elastically yieldable feeding movement to the cutters.

9. The method of making metal wool and shavings, consisting in mutually setting a circular series of shaving cutters and gages for progressively deeper cuts, bringing the cutters into cutting relation with a metal work-piece and the gages in co-operative relation thereto, effecting relative rotation between the work-piece and the cutters to pro-

- gressively cut shavings from the work-piece, and maintaining the work-piece and cutters in an elastically yieldable cutting relation.
10. The method of making metal wool and shavings, consisting in mutually setting a circular series of shaving cutters and gages for progressively deeper cuts, bringing the cutters into cutting relation with a metal work-piece and the gages in co-operative relation thereto, effecting relative rotation between the work-piece and the cutters to progressively cut shavings from the work-piece, and imparting an elastically yieldable feeding movement to the cutters.
15. 11. The method of making metal wool and shavings, consisting in bringing a plurality of shaving cutters and a work-piece into cutting relation, effecting relative movement between the work-piece and the cutters to cut shavings from the work-piece, and individually maintaining each cutter in an elastically yieldable cutting relation with the work-piece.
20. 12. The method of making metal wool and shavings, consisting in bringing a plurality of shaving cutters and a work-piece into cutting relation, effecting relative movement between the work-piece and the cutters to cut shavings from the work-piece, and imparting an elastically yieldable feeding movement to the cutters.
25. 13. The method of making metal wool and shavings consisting in mutually setting a circular series of shaving cutters and gages for progressively deeper cuts, bringing the cutters into cutting relation with a metal work-piece and the gages in cooperative relation thereto, effecting relative rotation between the work-piece and the cutters to progressively cut shavings from the work-piece, and individually maintaining each cutter in an elastically yieldable cutting relation with the work-piece.
30. 14. The method of making metal wool and shavings which consists in subjecting a work-piece to the simultaneous action of a plurality of shaving cutters set to cut shavings of predetermined thickness, and automatically maintaining the cutters and work-piece in their original cooperative cutting relations throughout the cutting operation.
35. 15. The method of making metal wool and shavings which consists in subjecting a work-piece to the simultaneous action of a plurality of shaving cutters set to cut shavings of predetermined thickness, and automatically maintaining the cutters and work-piece in their original cooperative cutting relations throughout the cutting operation by means of pressure.
40. 16. The method of making metal wool and shavings which consists in subjecting a work-piece to the simultaneous action of a plurality of shaving cutters set to cut shavings of predetermined thickness, and automatically maintaining the cutters and work-piece in their original cooperative cutting relations throughout the cutting operation.
45. 17. The method of making metal wool and shavings which consists in subjecting a work-piece to the simultaneous action of a plurality of shaving cutters set to cut shavings of predetermined thickness, and permitting the cutters to gravitate with respect to the work-piece to automatically maintain the cutters and work-piece in their original cooperative cutting relations throughout the cutting operation.
50. 18. The method of making metal wool and shavings which consists in subjecting a work-piece to the simultaneous action of a plurality of shaving cutters set to cut shavings of predetermined thickness, permitting the cutters to gravitate with respect to the work-piece to automatically maintain the cutters and work-piece in their original cooperative cutting relations throughout the cutting operation, and also applying additional pressure to the cutters.
55. 19. The method of making metal wool and shavings which consists in subjecting a work-piece to the action of a plurality of shaving cutters consecutively acting thereon, and independently and continuously feeding each cutter towards the work-piece with a uniform feed.
60. 20. The method of making metal wool and shavings which consists in subjecting a work-piece to the action of a plurality of shaving cutters consecutively acting on the same surface of the work-piece, and independently and continuously feeding each cutter towards the work-piece with a uniform feed.
65. 21. The method of making metal wool and shavings which consists in subjecting an end of a tubular work-piece to the action of a plurality of shaving cutters acting consecutively upon said end of the work-piece, and independently and continuously feeding each cutter towards the work piece with an elastically yieldable feed.
70. 22. The method of making metal wool and shavings which consists in subjecting a metal tube of a single thickness to the action of a plurality of shaving cutters acting consecutively upon an end of said tube, and independently and continuously feeding each cutter towards the tube.
75. 23. The method of making metal wool and shavings which consists in bringing a plurality of cutters into cutting relation with a work-piece, independently maintaining each cutter in a predetermined cutting relation to the work-piece and independently feeding each cutter with an elastically yieldable feed.
